Primary Examiner — Marianne N Pandozzi*(74) Attorney, Agent, or Firm* — Loeb & Loeb LLP(57) **CLAIM**

The ornamental design for an espresso coffee machine, as shown and described.

DESCRIPTION

FIG. 1 is a perspective view of a first embodiment of an espresso coffee machine showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof; and,

FIG. 8 is a perspective view of a second embodiment of the espresso coffee machine of FIG. 1, showing the top portion of the espresso machine is made from a transparent material. The broken lines in the drawing depict portions of the espresso coffee machine that form no part of the claimed design. The dot dash lines shown in FIG. 7 are for the purpose of illustrating the bounds of the claim and form no part thereof. The slanted shade lines shown on the indented rectangular portion in the front side of the espresso coffee machine are to indicate that the material is reflective. The other slanted shade lines shown in the drawings indicate that the material is transparent.
